UNITED STATES PATENT OFFICE.

GUY A. HERSEY, OF BANGOR, MAINE.

METALLIC SPOOL.

1,143,392.

Specification of Letters Patent. Patented June 15, 1915.

Application filed June 18, 1913. Serial No. 774,361.

To all whom it may concern:

Be it known that I, GUY A. HERSEY, a citizen of the United States, and a resident of Bangor, in the county of Penobscot and State of Maine, have invented a new and Improved Metallic Spool, of which the following is a full, clear, and exact description.

The invention relates to spools for containing sewing thread, yarns and the like, and its object is to provide a new and improved metallic spool which is simple in construction, cheap to manufacture and exceedingly light, yet strong and durable to allow repeated use of the spool.

In order to accomplish the desired result, use is made of an outer metallic shell and an inner metallic shell forming a reinforcing lining for the outer shell, each shell having a cylindrical body and tongues flaring outwardly and extending integrally from each end of a body to form a conical spool flange at each end of the spool, the tongues at the end of one shell being arranged in staggered relation to the tongues at the corresponding end of the other shell, each shell being formed from a sheet metal blank bent into cylindrical form with the edges of the body abutting and with the abutting edges of the shell bodies breaking joint. Use is also made of caps closing the ends of the shell, each cap having a crimping flange and the tongues at each end of the spool having crimping flanges arranged in a circle and interlocked with the crimping flange of the corresponding cap.

A practical embodiment of the invention is represented in the accompanying drawings forming a part of this specification, in which similar characters of reference indicate corresponding parts in all the views.

Figure 1 is a side elevation of the metallic spool with part in section and part of the paper covering broken out; Fig. 2 is a sectional plan view of the same on the line 2—2 of Fig. 1; Fig. 3 is a side elevation of one end of the assembled shells; Fig. 4 is a perspective view of the same and prior to crimping the flanges at the ends of the tongues; Fig. 5 is a face view of the blank for forming the outer shell; Fig. 6 is a sectional perspective view of a portion of the same; and Fig. 7 is an enlarged sectional side elevation of a portion of the cap and the crimping flange.

The metallic spool consists essentially of an outer shell A, an inner shell B and caps C

closing the ends of the shells. The shells A and B are formed from sheet metal blanks such as shown in Fig. 5, each blank being provided at the ends with parallel slits 60 forming tongues A', B' each terminating in a reduced crimping flange A² or B². The blanks are bent into cylindrical shape with the edges of the blanks abutting, and when the shells are assembled the tongues A' and B' are in staggered relation with each other and the abutting edges break joint, as plainly indicated at A³ and B³ in Fig. 2. In order to retain the shells A and B with the abutting edges of the shells breaking 70 joints and the tongues A' and B' in staggered relation during the bending operation, use is made of struck-up lugs A⁴ in the body of the shell A and bent inwardly to extend between the abutting edges of the inner 75 shell B so that the joints A³ and B³ are held in spaced relation one relatively to the other. It is understood that the cylindrical body of the inner shell B fits snugly against the inner surface of the cylindrical body of the 80 outer shell A, and the two assembled shells are subjected at each end to the action of a die press to swage the tongues A' and B' outwardly, as plainly indicated in Figs. 3 and 4, to form conical or flaring spool 85 flanges or rims at the ends of the cylindrical bodies. The crimped flanges A², B² are reduced in width relative to the width of the tongues A', B', to permit of swaging the said flanges into the form of a circle. Each 90 cap C is provided with an annular flange C' adapted to fit against the inner faces of the tongues B', the shoulder terminating in a crimping flange C² adapted to engage the crimping flanges A², B² and to be crimped 95 with the same outwardly by a suitable beading die-press, so that the parts are rigidly fastened together and securely held in position. Each of the caps C is provided with a central aperture C³ for the passage of the 100 supporting spindle for the spool when the latter is used. After the shells are assembled and fastened together as described the conical spool flanges at the ends of the cylindrical bodies are covered with a paper filling D to render the outer surfaces of the said spool flanges as smooth as possible, and then the cylindrical exterior surface of the cylindrical body of the outer shell A as well 105 as the said paper filling D are covered by a 110 paper covering E so as to protect the thread from coming in contact with the metal of

the spool. It is understood that by the arrangement described the tongue of one shell covers the space between adjacent tongues of the other shell to provide a continuous conical spool flange at each end of the spool. A metallic spool constructed in the manner described is exceedingly strong and durable yet comparatively light, and the spool can be cheaply manufactured.

10 Having thus described my invention, I claim as new and desire to secure by Letters Patent:

1. A metallic spool, comprising an outer metallic shell and an inner metallic shell 15 forming a reinforcing lining for the outer shell, each shell having a cylindrical body and rectangular tongues flaring outward from each end thereof, the tongues of the shells being in staggered relation to each 20 other and having shoulders on opposite sides adjacent to their ends, forming reduced crimping flanges, the flange of one shell extending between two adjacent flanges of the other shell, and a cap for each end of the 25 spool and provided with crimping flanges interlocking with the flanges of the said tongues.

2. A metallic spool, comprising an outer metallic shell and an inner metallic shell 30 forming a reinforcing lining for the outer shell, each shell having a cylindrical body, rectangular tongues flaring outwardly and extending integrally from each end of a body to form a conical spool flange, the adjacent edges of the shells breaking joints 35 with each other and the tongues at the end of one shell being arranged in staggered relation to the tongues at the corresponding end of the other shell and overlying one 40 another throughout their length, the said tongues at each end of the spool being reduced at their free ends to form crimping flanges lying adjacent to each other and arranged in a circle, and a cap for each end of

the spool and provided with an annular 45 outwardly extending flaring flange fitting against the inner faces of the tongues, the flange terminating in a crimping flange interlocking with the crimping flanges of the 50 tongues.

3. A metallic spool, comprising an outer metallic shell and an inner metallic shell forming a reinforcing lining for the outer shell, each shell having a cylindrical body, tongues flaring outwardly and extending 55 integrally from each end of a body to form a conical spool flange, the tongues at the end of one shell being arranged in staggered relation to the tongues at the corresponding end of the other shell, each shell being 60 formed from a sheet metal blank bent until the edges of the body abut, the abutting edges of the shell bodies breaking joint, and struck-up lugs on the outer shell body and extending inwardly between the abutting edges of the inner shell body to hold the shell bodies in joint-breaking relation 65 with each other.

4. A metallic spool, comprising two metallic cylindrical shells, each shell being 70 provided with outwardly flaring rectangular tongues having adjacent to their ends shoulders forming reduced crimping flanges, the shells being arranged one within the other 75 with their adjacent edges breaking joints 80 and the tongues being in staggered relation 85 to each other, means for securing the bodies of the shells together, and a cap provided with a crimping flange interlocking with the crimping flanges of the said tongues. 90

In testimony whereof I have signed my name to this specification in the presence of two subscribing witnesses.

GUY A. HERSEY.
